GIDEON B. MASSEY, OF NEW YORK, N. Y.

Letters Patent No. 87,183, dated February 23, 1869.

IMPROVEMENT IN LIQUID-METERS.

The Schedule referred to in these Letters Patent and making part of the same.

To all whom it may concern:

Be it known that I, GIDEON B. MASSEY, of the city, county, and State of New York, have invented a new and improved Liquid-Meter; and I do hereby declare that the following is a full, clear, and exact description thereof, reference being had to the accompanying drawings, making a part of this specification, in which—

Figure 1, sheet 1, is a diametrical section through the meter-case, and the measuring-vessel therein, exposing, by a side view, the measuring-mechanism, the supply-pipe, high-water float, and registering-case.

Figure 2, sheet 1, is a diametrical section through the meter-case and measuring-vessel, and the air-supplying device, exposing, by a front view, the measuring-devices and two valvular outlets, from the double-chamber measuring-devices.

Figure 3, sheet 1, is a sectional view of the oscillating water-way.

Figure 4, sheet 1, is a sectional view of the outlet from the lower section of the meter-case, and the valve for shutting this outlet when the water in the case rises too high.

Figure 5, sheet 2, is an enlarged sectional view of the automatic measuring-devices, which are applied to the double-chambered measuring-vessel within the meter-case.

Figure 6, sheet 2, is a top view of said measuring-devices, projected from fig. 5.

Similar letters of reference indicate corresponding parts in the several figures.

The object of my invention is to provide for accurately and cheaply measuring water, spirits, and liquids of various kinds, and to so construct the measuring-mechanism, that while it is certain in its operation and registration, it shall be controlled entirely by the flow of water through the chamber containing it, and operate equally as well under varying or constant heads or pressures of liquids.

The meter, which I shall hereinafter explain, is designed more especially for measuring and registering the measured quantity of water consumed for manufacturing, domestic, and other purposes, in cities and other places which are supplied with water from reservoirs; also for attachment to spirit-stills, that the quantity of taxable liquor manufactured may be measured, and a correct record of the same preserved.

The following description will enable others skilled in the art to understand the best means known to me for carrying my invention into effect.

For the purpose of elevating water or other liquid, after it is measured, above the level of the measuring-mechanism, and to take advantage of the head or pressure on the liquid, to effect this object, I apply the measuring-devices within an air-chamber, or globe, B, which may be made of metal or glass, and which is mounted upon the upper open end of a vessel, A, and secured air-tight thereon.

The vessel A is intended to receive the measured

liquid, and to allow the same to be drawn off through a pipe, W, to the inner end of which a valve, W', is applied, which is controlled by a float, O.

The float O is applied upon the upper end of a rod, O', which rod is pivoted to the longest end of the lever u of valve W', and this float is arranged so that, should the liquid rise high enough to obstruct the correct working of the measuring-devices, it will shut W', and prevent the liquid from escaping, or being drawn off through pipe W.

Under this condition of things, there will be too little air above the liquid in the casing; and in order to increase the quantity of air therein, I employ, on the outside of the receiver A, a chamber, K, communicating with the external air through pipe K' and cock 2, and with the interior of said receiver A, through pipe K' and cock 2'. By shutting cock 2, and opening cock 2', the air in chamber K will enter the casing A, B, and this chamber will be filled with water. Cock 2' is then shut, and cock 2 opened, which will allow the water to escape from chamber K, and air to take its place, which can be introduced into the casing, as before described.

In this way liquid can be drawn from the casing, and air introduced, until the liquid-level is at a proper distance below the float O.

The amount of air in the casing A, B should be such that, under the greatest pressure to which it will be subjected, it should not allow the liquid to rise above the float O, and if such an amount of air is maintained in the casing, the air-supplying chamber K, and its cocks, will not be required.

The liquid is conducted through a trap, on its way to pipe G, which trap contains a valve, U, that will prevent a reflux of liquid or air from the casing A, B, through the supply-pipe G.

The pipe G rises from a point near the bottom of the receiver A, nearly to the top of the air-chamber B, and is curved at its upper end, and provided with an outlet, g, arranged centrally over an oscillating chute, F, which I shall hereinafter term a water-way, and which is applied fast to a horizontal rock-shaft, f, mounted upon a double-chambered measuring-vessel, C, by means of bearings f' f'.

The water-way F consists of two disks, united by plates q, applied in such manner, shown in figs. 1 and 3, as to direct the descending stream into one or the other of the vertical chambers of the vessel C.

To one end of the rock-shaft f, a short arm, 8, is applied, by screwing it through this shaft, so as to lengthen or shorten its strokes, as may be required; and to this arm is pivoted a pawl-rod, P, which descends through a tube, P', fixed in one of the measuring-chambers, and has a tooth formed on its lower end, for actuating the ratchet-wheel T of the registering-mechanism.

The oscillatory motion given to shaft f, as will be hereinafter described, communicates a vertical motion

to pawl-rod P, and as the lower end of this rod is held in contact with the teeth on wheel T by a pivoted sheath or guide, T, this wheel will be turned a given distance at every descending stroke of the said pawl-rod P.

The registering-mechanism is contained within a box, M, which is water-tight, and which is applied within the receiver A, with its works exposed to view from the exterior of the receiver. Any suitable mechanism which will keep a correct record of the oscillations of shaft f, may be adopted.

The measuring-vessel C is divided diametrically by a partition, D, which forms two independent measuring-chambers, each one of which has an opening, j, through its bottom, which, at certain times, is closed by a valve, i.

These valves i are applied on the lower ends of rods I I, which rise through and are guided by the cross-pieces J, and which are pivoted at s s to the shortest arms of two vertically-vibrating levers, m m, shown clearly in figs. 5 and 6, sheet 2.

The levers m m have their fulcra at V, upon opposite sides of a vertical standard, l, and they are of an equal length, and receive equal length of strokes.

The longest arms of these levers m m have pivoted to them the bifurcated ends h h of two rods h' h', which rods are screwed through floats H H, so that these floats are suspended from said levers in their respective measuring-chambers of vessel C, as shown in figs. 2 and 5.

The lower portions of rods h' h' pass freely through the pieces J, and are guided by them.

The floats H H may be adjusted higher or lower on rods h' h', according to the height it is desired the liquid should rise in the measuring-chambers before being allowed to escape therefrom, through orifices j j.

It will be seen that the valve-rod I, applied to the valve i of one measuring-chamber, is attached to the shortest arm of the lever m, carrying a float, H, in the opposite measuring-chamber. Consequently, when a float, H, is caused to rise by the supply of liquid to its chamber, it will shut the valve i, in the opposite chamber, preparatory to the supply of liquid thereto.

To the rock-shaft f, of the water-way F, two arms, k k, are fastened on opposite sides of the standard l and a bridge, E, and to the free ends of these arms k k, rods n n are attached, by studs 5 5, passed through L-shaped slots made through them.

The outer ends of rods n n are pivoted, at p p, fig. 5, to the outer ends of levers m m, so that, by the alternate descent of the floats H, an oscillating motion will be given to the shaft f and the water-way F.

The inner ends of rods n n are slotted, as shown in the drawings, for the purpose of allowing either float, H, to rise to its full height without acting upon the arm k, to which it is connected by a rod, n; also, to allow the inner ends of said rods to drop, by their own gravity, far enough to press against pins t, on arms k, and thus hold these arms positively in their proper position during the filling of one chamber and the emptying of the other.

To the pivots s s, on the short arms of levers m m, latches r r are applied, the opposite bevelled ends of which latches are passed freely through slots made through the pivot-heads p p, on levers m m, as shown clearly in figs. 5 and 6.

The object of these latches r r is to arrest each float, H, when it arrives at its highest point, and retain it there until the opposite float reaches its highest point, thereby keeping the valve i, which is in the chamber receiving liquid, shut, until this chamber receives its supply, and the valve in the opposite chamber is shut. In this manner the measuring-chamber will alternately receive and discharge a full and equal supply of liquid.

The latches r r catch over points of repose, e, on

pivoted rests e, which have their bearings on the depressed ends of the bridge E, and the screws e, applied to rests e, admit of their being adjusted to a nicety, for arresting and releasing the bevelled ends of said catches at proper times.

The bridge E is secured at its ends to the upper part of the measuring-vessel C, and crosses this vessel at right angles to the plane of the partition D, and receives through it the rock-shaft f of the water-way F.

By reference to the diagram, fig. 5, and the following description, the operation of the latches r r will be understood.

When one of the floats, H, is arrested by its latch r, the other float is free to drop or ascend.

In the diagram just referred to, this condition of things is shown, to wit, one of the floats, H, is represented as ascending, and the centre of its pivot-attachment p, with lever m, describing the arc X and P, the pivot-attachment s of this lever m, with the valve-rod I, describing the arc Z.

When said float reaches the termination of its ascending stroke, the catching-end of its latch, r, which describes arc Y, will be in a position to catch on its rest e, and will be thrust outwardly over its rest at the instant the catch r, applied to the opposite float H, is detached from its rest e, and this float allowed to drop.

The same operation is repeated as the floats alternately rise to a given height, by the supply of liquid to their respective chambers.

The pivoted rests e are inclined, so that they will retreat slightly when pressed against by the bevelled ends of the latches r r, and allow these ends of the latches to rise above them, after which they will drop beneath the latches by their own gravity.

The latches are released from their rests by the descent of the shortest arms of levers m m, to which they are respectively pivoted, as above described, and at the instant of release of a latch, its float drops and shifts position of the water-way F, so as to guide the liquid into the measuring-chamber last emptied.

When it is not desired to force the measured liquid to a point above the level of the meter, as, for instance, in measuring spirits flowing from stills, the air-tight casing A B may be dispensed with, and the chambered vessel C constructed so as to be properly attached, at its upper end, to a supply-pipe, and to discharge the liquid from its lower end into a suitable receiver.

Operation.

Liquid is conducted through pipe G, and discharged from its orifice g upon the water-way F, which guides it into one of the apartments of the vessel C.

When the liquid rises in such apartment to a given height, regulated by adjusting the float H upon its rod h, this float will be elevated to its highest point, and will be caught and held up by its latch r, extending over the rest e.

During the ascent of the float H, the valve-opening j, in the opposite empty chamber, will be shut.

At the instant the float H, in the filled chamber, is caught at its highest point, the opposite float H will be released and allowed to drop, in doing which it will raise the valve i, in the filled chamber, and shift the water-way F, so as to guide the liquid into the empty chamber, which latter will be receiving liquid while its opposite chamber is discharging its contents.

In this way, the measuring-chamber of vessel C will be alternately filled and emptied, and each measured quantity will be registered by the mechanism in the box M, which is operated by rock-shaft f, acting through the medium of pawl-rod P, and ratchet-wheel T, as before described.

Having described my invention,

What I claim as new, and desire to secure by Letters Patent, is—

1. Stationary measuring-chambers C C and floats H H, in combination with valves *i i* and suspending-devices *r e*, substantially in the manner and for the purpose described.

2. The rods *n n*, connected to arms *k k*, on the rock-shaft of the water-way F, and also connected to the ends of levers *m m*, in combination with floats H, arranged in the double-chambered vessel C, whereby the alternate descending movements of the said floats will

shift the flow of liquid from one measuring-chamber to the other, substantially as described.

3. The combination of the slotted rods or arms *n*, wrist-pins *s*, arms *k*, and stop-pins *t*, substantially as described.

GIDEON B. MASSEY.
